UNITED STATES PATENT OFFICE.

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS.

DESIGN FOR A MOTION-PICTURE-CAMERA CASE.

Application filed February 27, 1928. Serial No. 25,604. Term of patent 14 years.

To all whom it may concern:

Be it known that I, ALBERT S. HOWELL, a citizen of the United States, residing at Chicago, in the county of Cook and State of Illinois, have invented a new, original, and ornamental Design for a Motion-Picture-Camera Case, of which the following is a specification, reference being had to the accompanying drawings, forming a part hereof.

In the said drawings—

picture camera case embodying my new design.

Figures 2 and 3 are opposite side elevations of the same.

Figure 4 is a rear elevation of the same.
I claim:

The ornamental design for a motion picture camera case, as shown.

In witness hereof I hereunto affix my signature this twentieth day of February, A. D. 1928.

ALBERT S. HOWELL.
